MAGNET RELEASE FOR STARTING GATES

Bryant Steele, Keenland, Ky., assignor to David E. White, Cleveland, Ohio

Original application July 12, 1940, Serial No. 345,219. Divided and this application July 15, 1942, Serial No. 450,995

9 Claims. (Cl. 292—1)

This device relates to a release means for releasing the parts of a permanent magnet, constructed for instance of the compositions disclosed in the Ruder patents, Numbers 1,947,274 and 1,968,569; Mishima patents, Numbers 2,027,994 to 2,028,000 inclusive, and the Howe patent, Number 2,192,743, although the invention is not limited to the use of the compositions disclosed in these patents except as set forth in the claims. Magnets constructed in accordance with the teachings of one or more of these patents have been called by the term of "Alnico metal magnets" or "sintered Alnico metal magnets." These magnets have been of the permanent magnet type, and no means has heretofore been devised to cause the release of the magnet forces of the magnets.

The present application is a division of my copending application Serial No. 345,219, filed July 12, 1940.

An object of the present invention is to provide a means for releasing the magnet forces of, or demagnetizing, a permanent magnet, such as an "Alnico metal magnet."

Another object of the invention is to provide a race horse starting gate having doors for the release of the horses provided with permanent magnets, such as magnets of Alnico metal with means for effecting the release of, or demagnetization of the magnets.

Other objects will appear hereinafter.

In the drawings:

Figure 1 is a plan view of a pair of doors of a starting gate provided with the device of my invention.

Figure 2 is an elevational view of the magnet release device shown detached from the doors of Fig. 1 for clarity of illustration.

Figure 3 is a top plan view of the device shown in Figure 2, certain parts being shown in section.

Figure 4 is a top plan view of a modification of the device shown in Figures 2 and 3.

Figure 5 is a detail plan view of the magnet block.

Figure 6 is a front elevational view of a starting gate showing the invention applied in slightly modified form.

In the drawings the numeral 1 indicates a mounting block or base preferably constructed of brass, and provided with side plates 2.

The base is provided with a recess 3 for the reception of the magnet block 4 which is retained in the recess in fixed position by suitable means such as the screws 5 which are mounted in the side plates.

The magnet block may be made in any suitable manner for holding the Alnico or other magnetic material, but I prefer to construct the same as shown in Figure 5, wherein 6 is a brass or bronze alloy center portion partially surrounded by a steel or other ferrous metal portion of general horse-shoe configuration. The numeral 9 indicates spaces for the reception of brass strips 10 which do not extend all the way to the end of the magnet block at one of their ends, and which connect with or abut the brass center portion at their other ends.

Set into the steel or other ferrous metal portion is the sintered Alnico magnetic plug 8, an alloy composed of aluminum, nickel, iron and cobalt, in accordance with the above enumerated patents.

The side plates 2 mount bearing portions 12 each of which is provided with an elongated slot 13 in which seat the pins 14 that extend from each side of the secondary short-circuiting armature or release plate 15. This plate is therefore pivotally mounted in the slots 13. The plate is provided adjacent its other end with an upstanding ear 16 having an aperture 17 for the reception of the nose 19 of the latch arm 18 as shown in Figures 2 and 3.

The electro-magnet is indicated at 20 and is provided with a core 21 which, when energized, pulls the latch arm downwardly (Figure 2), to release the nose from the aperture 17 to thereby permit the spring 22 to force the secondary armature into contact with one side of the magnet block. The spring 22 is mounted on top of the base 1.

The primary armature is designated by the numeral 23. This preferably consists of a central bronze portion 24 having fixedly attached thereto a ferrous metal portion 25 and on the opposite side another ferrous metal portion 26. The ferrous metal portion 25 consists of a series of blocks providing slots 27. Strips of bronze material 28 extend almost to the edge of the slots and connect or abut at their opposite ends with the central bronze portion 24.

The primary armature may be guided in its movements toward the magnet block 4 by a metal strap 29 secured to the side plates 2 by screws 30.

The electro-magnet shown may be of any well known construction and may also be mounted as shown in the alternative construction shown in Figure 4 wherein one of the side plates is indicated at 31. These plates are similar to the plates 2 and are provided with ears 32 having elongated slots 33 in which are mounted the pins

34 forming the pivots for the secondary armature or release plate 35. The electro-magnet is indicated by the numeral 36 and is mounted on the arm 37, which latter is affixed by suitable means such as the screw 38 to the base 39. The secondary armature is urged to its closed position by the spring 40 which is mounted on the base by means of the screw 41. The electro-magnet is provided with a core 42.

The primary armature is indicated by the numeral 43. This armature is the same or similar to that disclosed in Figures 2 and 3 and may be guided towards the magnet block, which is not illustrated but which is the same as that shown in Figure 3, by the strap 44 which is affixed to the base by screws 45.

I have shown in Figure 1 one use to which my invention may be applied. The numerals 46 and 47 indicate pivoted doors of the type illustrated in my Patent No. 2,193,257, granted March 12, 1940. As illustrated, the primary armature 23 is mounted on a supporting strap 48 connected adjacent to the end of the door 46. The magnet and release shown in Figures 2 and 3 are mounted adjacent to the juxtaposed end of the other door 47. The electro-magnet 20 is mounted on an arm 49 which is also affixed to the door 47. An electric circuit is indicated by the numeral 50 having a source 51 and a manually operated switch 52.

It will be apparent that upon completion of the circuit by operating the switch 52, the latch 18 will be withdrawn from the aperture 17 whereupon the spring 22 will immediately force the secondary armature 15 upwardly as viewed in Figures 1 and 3. The magnetic flux which has passed through the primary armature from the magnet will now be diverted or shunted and will pass through the plate 15. In other words the flux path will pass through the plate 15 instead of passing through the primary armature 23. When this occurs the springs tending to open the doors 46 and 47 (shown in Figure 3 of my prior patents above) will immediately cause the opening of said pair of doors in the same manner as described in my patent. It is to be understood that there are as many pairs of doors as shown in Figure 1 as there are stalls. It is of course obvious also that each magnet may be controlled from a single circuit as indicated in Figure 5 of my patent.

Figure 6 shows another manner of applying my invention to a starting gate for race tracks. In the figure, 54 and 55 indicate vertical posts pivotally mounted to the superstructure 53 and partitions 62 and 63. Rigidly mounted on these posts so as to swing therewith are the doors 56 and 57.

The arms 58 and 59 are rigidly mounted on the posts 54 and 55 respectively and swing therewith. When the doors are in closed position as indicated in the figure the magnet 60 mounted on the arm 58 and the primary armature 61 mounted on the arm 59 contact each other and hold the pair of doors 56 and 57 in closed position until the electro-magnet is operated to release the armature 61 from the magnet 60. The doors are opened by springs not shown but as indicated in Figure 3 of my patent above referred to. The magnet and electro-magnet diagrammatically illustrated in Figure 6 are the same in detail as those disclosed in Figures 2, 3 or 4 of the application.

It will be noted that in the structure shown by Figures 2 and 3 the secondary armature is

held in its open position by the latch 18 until the current is turned on. When the current is turned on the latch 18 is drawn downwardly to release the said secondary armature. In Figure 4 however no latch is provided, and the secondary armature 35 is retained in its open position as long as the current is on so that the core 42 is energized by current in the magnet 36.

It is to be understood that the term "electro-magnetic means" in the claims refers to the parts 18, 19 and 20 shown in Figures 2 and 3, or the parts 36 and 42 in Figure 4.

In each form of embodiment the device may be manually reset to the position of Fig. 3 or Fig. 4. In the Fig. 3 device the secondary armature 15 is retracted against the spring 22 to engage the latch parts 19 and 17. In the Fig. 4 device the secondary armature 35 is pulled back while the circuit to the coil 36 is closed.

It is to be understood that the device of the present invention may be used not only on gates for starting horses at a race track, but that the magnet release of this invention may be used for any purpose to which it is applicable. Other uses to which my invention may be put include its application for use with a magnet chuck, or in fact any use which includes a permanent magnet or an electro-magnet.

I claim:

- 30 1. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature mounted adjacent to the permanent magnet and movable between an inoperative position spaced from the permanent magnet and an operative position shunting the magnetic flux of the permanent magnet, and electro-magnetic means for controlling movement of the secondary armature.
- 35 2. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature mounted adjacent to the permanent magnet and movable between an inoperative position spaced from the permanent magnet and an operative position shunting the magnetic flux of the permanent magnet, means biasing the secondary armature to operative position, a latch for holding the secondary armature in inoperative position, and electro-magnetic means for releasing the latch.
- 40 3. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature mounted adjacent to the permanent magnet and movable between an inoperative position spaced from the permanent magnet and an operative position shunting the magnetic flux of the permanent magnet, means biasing the secondary armature to operative position, and electro-magnetic means adapted when energized to hold the secondary armature, against the action of the biasing means, in inoperative position.
- 45
- 50
- 55
- 60
- 65
- 70
- 75

4. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature pivoted adjacent to the permanent magnet to swing away from the permanent magnet to an inoperative position and to swing toward the permanent magnet to an operative position shunting the magnetic flux of the permanent magnet, and electro-magnetic means controlling movement of the secondary armature.

5. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature pivoted adjacent to the permanent magnet to swing away from the permanent magnet to an inoperative position and to swing toward the permanent magnet to an operative position shunting the magnetic flux of the permanent magnet, means biasing the secondary armature toward operative position, a latch for holding the secondary armature in inoperative position, and electro-magnetic means controlling movement of the secondary armature.

6. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature pivoted adjacent to the permanent magnet to swing away from the permanent magnet to an inoperative position and to swing toward the permanent magnet to an operative position shunting the magnetic flux of the permanent magnet, means biasing the secondary armature toward operative position, and electro-magnetic means adapted when energized to hold the secondary armature in inoperative position.

7. The combination, with a pair of hinged doors having free edges adapted to meet in a dihedral angle less than a straight angle when

5 the doors are closed, of a permanent magnet mounted in substantially fixed relation to one of the doors, a primary armature mounted in substantially fixed relation to the other door, said magnet and armature being positioned to engage each other in lengthwise alignment when the doors are closed, and a guide for the armature mounted adjacent to the magnet to interengage with the armature to prevent relative lateral displacement of the armature and magnet when engaged.

8. The combination, with a pair of hinged doors having free edges adapted to meet in a dihedral angle less than a straight angle when the doors are closed, of a permanent magnet mounted in substantially fixed relation to one of the doors, a primary armature mounted in substantially fixed relation to the other door, said magnet and armature being positioned to engage each other in lengthwise alignment when the doors are closed, and a guide for the armature fixed adjacent to the magnet and including an opening adapted to be penetrated by the armature and surrounded by a rigid wall engaging with the armature to prevent relative lateral displacement of the armature and magnet when engaged.

9. The combination with a pair of cooperating door members of a permanent magnet mounted in substantially fixed relation to one of the members and a primary armature mounted in substantially fixed relation to the other member for engagement with the permanent magnet when the members are in closed relation, a secondary armature pivoted adjacent to the permanent magnet to swing away from the permanent magnet to an inoperative position and to swing toward the permanent magnet to an operative position shunting the magnetic flux of the permanent magnet, a spring biasing the secondary armature toward operative position, an apertured ear extending from the face of the secondary armature opposite the permanent magnet, a movable latch arm engageable in said aperture for holding the secondary armature in inoperative position against the opposition of the spring, and an electro-magnet adapted when energized to move the latch arm out of the aperture and release the secondary armature for movement by the spring toward operative position.

50 BRYANT STEELE.
